HEAT INDICATOR

Leonard Boddy, Ann Arbor, Mich., assignor to
 King-Seeley Corporation, Ann Arbor, Mich., a
 corporation of Michigan

Application July 6, 1931, Serial No. 549,074

4 Claims. (Cl. 73—52)

The invention relates to indicating devices and refers more particularly to devices having a movable column of indicating liquid within a transparent tube. One of the objects is to so construct the device that it indicates at a point remote from that causing movement of the indicating liquid. Another object is to so construct the device that it is accurate in operation and its indicating liquid is effectively retained. A further object is to so construct the tube for placing the bulb and the transparent tube of the device in communication that the communicating and transparent tubes are directly hermetically sealed to each other. These and other objects of the invention will become apparent from the following description, taken in connection with the accompanying drawing, in which

Figure 1 is a side elevation, partly in section, showing a heat indicator embodying my invention;

Figure 2 is a front elevation thereof;

Figure 3 is an enlarged sectional detail view of the bulb of the heat indicator;

Figure 4 is an enlarged sectional detail view of the adapter;

Figure 5 is a view similar to Figure 1, showing a modified construction.

My invention, as illustrated in the present instance, is embodied in a heat indicator which is specifically shown as applied to an internal combustion engine of a motor vehicle. In detail, the heat indicator has the bulb 1, the transparent tube 2 and the tube 3 between the bulb and the transparent tube for placing the same in communication.

The bulb 1 may be suitably secured to the engine in either a horizontal or vertical position to extend within its water jacket and this bulb comprises the hollow body 4 formed of suitable metal, such as brass. The body has the closed end 5 and the cap 6 also formed of suitable metal, such as brass, and permanently secured to the open end of the body. The cap 6 preferably has the bevelled annular shoulder 7 for engaging the bevelled annular shoulder 8 formed in the opening of the outer wall of the engine and the shoulder 7 is clamped against the shoulder 8 by suitable means, such as the nut 9 threaded into the outer wall and abutting the cap 6, thereby securing the bulb in place.

The transparent tube 2 is a glass tube and is vertically mounted in the metal support or head 10, which carries the graduations 11 at one side of the glass tube for indicating the degree of heat or temperature of the cooling medium in the

water jacket of the engine. The glass tube is frictionally secured to the support by the resilient bifurcated clamp 12 secured to the back of the support and having its bifurcations or fingers embracing and resiliently engaging the glass tube 5 near its upper end.

The tube 3 comprises the capillary tube sections 13 and 14 formed of suitable metal, such as copper, and the adapter section 15 formed of suitable metal, such as brass, and connecting 10 the adjacent end portions of the tube sections 13 and 14. The adapter section has the axially aligned recesses or bores 16 and 17 and the intermediate axially aligned capillary passageway 18 and the tube sections 13 and 14 have adjacent end 15 portions respectively engaging in the recesses or bores 16 and 17 and abutting the shoulders formed at their inner ends, by means of which the tube sections are properly located in the adapter section and pockets within the adapter section 20 for collecting air are eliminated. These tube sections are suitably secured to the adapter section as by solder. The adapter section 15 is mounted upon and secured to the back of the support 10 and the tube section 13 is preferably formed with the vertically extending U-portion below the glass tube. This tube section, being pliable, may be readily bent to raise or lower the glass tube with respect to the graduations 11. The other end portion of the tube section 14 extends into 30 the recess or bore 19 in the cap and abuts an annular shoulder formed at the inner end of the recess or bore, eliminating any pocket in the cap for trapping air. This end portion is suitably secured to the cap as by solder. 35

The tube section 13 has the vertically extending end portion 20 which is hermetically sealed directly within the lower end portion of the glass tube 2. This is accomplished by holding the end portion 20 and the lower end portion of the glass 40 tube 2 adjacent to each other and subjecting the same to a proper flame to oxidize the end portion 20 and reduce the inner diameter of the lower end portion of the glass tube, so that the latter encircles and fuses upon and is welded 45 to the former when properly oxidized. To take care of the cooling of the tube section 13 and glass tube 2 after they have been fused and welded together without destroying the seal or breaking the glass tube, the tube section 13 is formed 50 with a relatively thin wall as compared to that of the tube section 14 with the result that while the external diameters of these tube sections are substantially the same the internal diameters appreciably differ with the internal diameter of 55

the tube section 13 the larger. The thickness of the wall of this tube section 13 as compared to its diameter is such that the material forming the tube section will yield during the cooling 5 to remain with the glass.

For supporting and protecting the tube section 14, I have provided the pliable coil 21 encircling this tube section and encircling and mounted at its ends upon the nipple 22 of the 10 cap 6 and the nipple 23 of the adapter section 15.

The cap 6 has an opening therethrough for placing the tube section in communication with the interior of the hollow body 4 and this opening comprises the capillary passageway 24 at 15 the end of the tube section 14 and the outwardly flared passageway 25 extending from the capillary passageway to the inner end of the cap. By reason of this construction trapping of air within the bulb is avoided in the operation of 20 the heat indicator, so that the correct temperature will be indicated.

To effectively secure the cap 6 to the body 4 and also to avoid the entrance of material into the body which might enter and clog the capillary passageway in the cap, I have provided the 25 inner end portion of the cap with the external annular flange 26 and the external annular groove 27 with the flange innermost and of a diameter slightly greater than the internal diameter of 30 the body and having a force fit with the body. The end of the body is formed with one or more notches 28 through which solder may pass into the groove, the flange preventing the solder from 35 entering the body.

The indicating liquid fills the bulb 1 and the tube 3 and extends upwardly within the glass tube 2 to a predetermined height within this tube at a predetermined temperature and in order to take care of the different commercial 40 internal diameters of the glass tube the body 4 of the bulb preferably has its open end portion cut off at different distances dependent upon the internal diameter of the glass tube to secure a predetermined ratio of volume of the body of the bulb to volume of the glass tube for a predetermined length. Another method of securing this 45 result, as shown in Figure 5, is to insert within the bulb one or more displacement members having a predetermined volume and a coefficient of expansion less, and preferably considerably less, 50 than that of the indicating liquid.

The upper end of the glass tube is hermetically sealed so that the portion of the glass tube above the indicating liquid is filled with air which, upon expansion of the indicating liquid 55 by reason of subjecting the bulb to an increased temperature, creates a pressure upon the indicating liquid to assist in returning the same to normal position upon cooling of the bulb. Fur-

thermore, by reason of the hermetically sealed upper end of the glass tube, loss of the indicating liquid by evaporation is prevented and the boiling point of the indicating liquid is raised and also entrance of impurities, such as moisture, dirt, etc. into the indicating liquid is prevented, thereby avoiding rendering the heat indicator inaccurate or inoperative.

What I claim as my invention is:

1. In an indicating device, the combination 10 with a glass tube, of a metal tube member having an end portion extending within and hermetically sealed directly to said glass tube by fusing and welding, said tube member having such wall thickness that the material forming 15 the tube will yield to avoid breaking the seal upon contraction of the glass tube during cooling, and said glass tube and metal tube member adapted to contain an indicating liquid.

2. In an indicating device, the combination 20 with a glass tube, of a metal tube connected to said glass tube and comprising a metal tube section having an end portion extending within and hermetically sealed directly to said glass tube by fusing and welding, the end portion of 25 said tube section having such wall thickness that the material forming the same will yield to avoid breaking the seal upon contraction of the glass tube during cooling, a second metal tube section, and means connected to adjacent ends of said 30 metal tube sections having a passageway therethrough in communication with said metal tube sections.

3. In an indicating device, the combination 35 with a glass tube, of a tube member having a yieldable end portion extending a substantial distance within and having an extended contact with said glass tube, said end portion being hermetically sealed directly to said glass tube by fusing and welding, said end portion also being 40 sufficiently yieldable to avoid breaking the seal upon contraction of the glass tube during cooling and said glass tube and tube member adapted to contain an indicating liquid.

4. In an indicating device, the combination 45 with a glass tube, of a metal tube connected to said glass tube and comprising a metal tube section having an end portion extending within and hermetically sealed directly to said glass tube by fusing and welding, said tube section 50 having such wall thickness that the material forming the tube section will yield to provide for limited adjustment of the glass tube, a second metal tube section, and an adapter connecting the adjacent ends of said metal tube section and 55 having a passageway therethrough in communication with the latter sections.

LEONARD BODDY.
